(57) **CLAIM**

The ornamental design for an undulated medical instrument handle, as shown and described.

DESCRIPTION

FIGS. 1, 2, 3, and 4 are side elevations at 90 degree offsets of an undulated medical instrument handle showing our new design;

FIG. 5 is a front to back perspective view thereof;

FIG. 6 is a front view thereof; and,

FIG. 7 is a back view thereof.

The broken lines showing the remainder of the medical instrument are directed to environment and are for illustrative purposes only; the broken lines form no part of the claimed design.
